CLAIM

The ornamental design for a bottle screw top, as shown and described.

DESCRIPTION

FIG. 1 is a front perspective view of a first embodiment of a bottle screw top, showing my design;

FIG. 2 is a front-left perspective view thereof;

FIG. 3 is a front-left perspective view of a second embodiment of a bottle screw top;

FIG. 4 is a front perspective view thereof;

FIG. 5 is a top plan view thereof; and,

FIG. 6 is a right perspective view thereof, the left side being a mirror image thereof.
